UNITED STATES PATENT OFFICE

2,435,791

ROTARY PRINTING PRESS

Hans J. Luehrs, Westerly, R. I., assignor to C. B. Cottrell & Sons Company, Westerly, R. I., a corporation of Delaware

Continuation of application Serial No. 440,917, April 29, 1942. This application May 16, 1944, Serial No. 535,780

9 Claims. (CL 101—180)

1

My invention consists in a multicolor rotary printing press which may be readily converted to print on one or both sides of a traveling web as desired, without requiring material changes in the press structure. This application is a continuation of application Serial No. 440,917, filed April 29, 1942, since abandoned.

My invention is directed more particularly to a convertible printing press in which certain of the mechanisms may be rearranged or substituted by other printing mechanisms to print with any selected kind of ink whereby aniline, rotogravure, oil ink, or offset printing may be produced, as desired.

My invention is also directed to a printing press of the above character in which the press is provided with gears, guide rolls and feed rolls which may be located in either the lower or upper position for accomplishing the perfecting or non-perfecting of the traveling web, respectively.

In the accompanying drawings, Fig. 1 represents a diagram of my convertible printing press arranged for typographic or letter press printing with aniline inks and adapted to print six colors on one side only of a traveling web. Fig. 2 represents a side view of the gearing for driving the press when the parts are arranged as shown in Fig. 1. Fig. 3 represents a diagram of the press shown in Fig. 1 when converted to print two colors on one side of the traveling web and three colors on the other side thereof. Fig. 4 represents a side view of the gearing for driving the press when the parts are arranged as shown in Fig. 3. Fig. 5 represents a detail diagram of the convertible press when arranged for rotogravure printing in the upper units, mono-roll aniline printing in the intermediate units and standard aniline printing in the lower units, when adapted to print six colors on one side only of the traveling web. Fig. 6 represents a side view of the gearing for driving the press when the parts are arranged as shown in Fig. 5. Fig. 7 represents a diagram showing the parts arranged for perfecting all typographical printing with oil inks. Fig. 8 represents a diagram of the convertible press when arranged for perfecting for offset or transfer printing.

The printing press as a whole includes the base frames 10, the top frames 11, the roll frames 12, the press frames 13, and the side brackets 14 of the desired sizes, which brackets project to the right and left from the press frames 13. In Fig. 1 I have shown six short brackets 14, 55

2

arranged in two vertical stacks of three brackets each.

The web supply roll 15 and the printed web rewind roll 16 are both shown as being carried by the roll frames 12. A series of guide rollers 17 are carried by the roll frames 12 and the top frames 11 for leading the web from the supply roll 15 to the upper pair of selectively used web feed rolls 18, 19, when the web is to be printed in six colors on one side only, as shown in Fig. 1.

A series of guide rollers 20 are carried by the base frames 10 for leading the web from the supply roll 15 to the lower pair of selectively used web feed rolls 21, 22, when the web is to be printed in two colors on one side and three colors on the other side thereof, as shown in Fig. 3.

Another series of guide rollers 23 are carried by the top frames 11 and serve to lead the printed web from the pair of feed rollers 24, 25 to the pair of feed rollers 26, 27 on its way from the printing units to the printed web rewind roll 16, whether the web be non-perfected or perfected.

Each of the aniline ink printing units which are mounted on the short brackets 14 shown in Figs. 1 and 3 are shown as comprising an ink fountain 28, fountain roll 29, transfer roll 30, printing cylinder 31 of a selected size and its impression cylinder 32.

The drive for the six aniline printing units illustrated in Fig. 1 is shown in Fig. 2. The cross shaft 33 drives the rewind roll 16 through the pulley 34, belt 35, pulley 36 and gears 37, 38, 39. This cross shaft 33 also drives the longitudinal shaft 40 through the bevel gears 41, 42. This longitudinal shaft 40 drives each of the printing units through the bevel gears 43, 44, cross shaft 45 and gears 46, 47, 48, 49, 50, 51, 52, 53, the gear 50 being common to all the gears 51. It will be understood that the gears 51 for the printing units mounted on the right hand projecting brackets 14 are gears which may be relocated for the purpose of reversing the travel of the web through these two printing units when the web is to be perfected, as shown in Fig.

4. They also serve as adjusting gears for their respective printing units. Likewise the feed rolls 18, 19 may also be relocated for perfecting the web to the feed rolls 21, 22, as shown in Fig. 3.

The upper pair of web feed rolls 18, 19, when used, may be driven from the gear 50 through the gears 54, 55. The pair of web feed rolls 24, 25 for the printed web may be driven from the gear 55 through the intermediate gear 56 and the gear 57 on the shaft 58 of the feed roll 24. The other pair of web feed rolls 26, 27 for the printed web

are driven from this shaft 58 of the feed roll 24 through the bevel gears 59, 60, cross shaft 61 and bevel gears 62, 63.

The lower pair of web feed rolls 21, 22, when used for perfecting the web, may be driven from a gear 64 on the shaft 65 of the gear 49 through the gears 66, 67.

In Fig. 5 I have shown the web in full lines arranged for being printed in rotogravure in the upper units, mono-roll aniline printing in the intermediate units and standard aniline printing in the lower units in six colors on one side only, and in broken lines arranged for being printed in two colors on one side and three colors on the other side of the web. Otherwise the arrangement of the printing units and the drive therefor are similar to the embodiments illustrated in Figs. 1 and 2.

In the form shown in Figs. 5 and 6, the two upper printing units have their gravure printing cylinders 31 of a selected size partly enclosed in the ink fountains 68, said cylinders being directly contacted by the fountain rolls 29. In the two intermediate printing units the plate cylinders 31 which are located exterior to the ink fountains 69 are directly contacted by the fountain mono-rolls 29. In the two lower printing units the fountain rolls 29 and the transfer rolls 30 are located within the ink fountains 70, and the plate cylinders 31 are located exterior to the ink fountains in contact with the transfer rolls 30.

In Fig. 7 I have shown the press as arranged for typographic printing in four colors, with oil inks. In this instance the two intermediate printing units have been removed and the web is shown in full lines arranged to be printed in four colors on one side only of the web, and in broken lines arranged to be printed in two colors on both sides of the web.

In this form each printing unit is shown as comprising an ink fountain 71, its fountain roll 72, the ductor roll 73, distribution rolls 74 and form rollers 75.

It will be seen that in all of the forms, the inking mechanisms are mounted on the brackets 14 of the selected size projecting to the right and left from the press frames 13, thus rendering the press readily convertible for different types of printing with no change in the press frames, the impression cylinders and the drive.

In Fig. 8 two colors are printed in offset on the first side of the web and both a tint and a single color on the second side of the web. In this form the first, second and fourth printing mechanisms include the ink fountains 76, the working-up rolls 77, the plate cylinders 78, the transfer cylinders 79 and the dampening devices 80. The color tinting unit is shown as comprising the fountain 81, the ink transfer cylinder 82 and the printing cylinder 83.

Referring to the form shown in Figs. 1 to 4 inclusive, it will be seen that when the web is to be printed in six colors on one side only of the web the upper pair of web feed rolls 18, 19 are driven. It will also be seen that when the web is to be printed in two colors on one side and three colors on the other side, the lower pair of web feed rolls 21, 22 are driven. In this arrangement the gears 51 for the upper and lower printing units for the first side printing are shifted from their positions shown in Fig. 2 to the positions shown in Fig. 4 so as to reverse the movement of the upper and lower plate cylinders 31 and their respective impression cylinders 32.

It will be noted that when the lower gear 51 is

shifted to its new position shown in Fig. 4 it will be brought into mesh with the gear 64 instead of the gear 50, and the upper change gear 51 will be brought into mesh with the gear 54 instead of the gear 50.

It will also be noted that in Fig. 1 the changeable brackets 14 are shown of a size to suit a printing unit of a certain selected type. In Fig. 3 the intermediate bracket 14 and its printing unit in the first stack are omitted. In Fig. 7 the brackets 14 are shown of a different size from those shown in Fig. 1. Also the intermediate brackets 14 and their printing units in both stacks are removed.

It will be understood that changes similar to those hereinbefore referred to with respect to the embodiment shown in Figs. 1 to 4 inclusive will be made in the drives for the embodiments shown in the remaining figures whenever the web is to be perfected instead of non-perfected.

It will also be understood that one pair of feed rolls may be changeably located in the upper and lower position according to the direction the web is to be fed instead of selectively using two pairs of these feed rolls.

A platform 84 may be provided on the base frame 10 for facilitating the access of the operator to the right hand stack of printing units.

From the above description it will be seen that the web may be easily adapted for printing on one or both sides thereof with different kinds of ink, with the least possible disturbance of the press structure and the operative elements thereof.

It is evident that various changes may be resorted to in the construction, form and arrangement of the several parts without departing from the spirit and scope of my invention, and hence I do not intend to be limited to the particular embodiment herein shown and described, but

What I claim is:

1. In a rotary multicolor printing press, base frames, top frames, roll frames and press frames, changeable brackets projecting to the right and left from the press frames, a web supply roll, two upper series of web guide rollers carried by the top and roll frames and a lower series of web guide rollers carried by the base frames, two adjacent stacks of printing units carried by the press frames, means for leading the web over one of the upper series of guide rollers, through both stacks of the printing units and over the other upper series of guide rollers for non-perfected the web and over the lower series of guide rollers, through both stacks of the printing units and over said other upper series of guide rollers for perfecting the web, and means for reversing the movement of one stack of the printing units when perfecting the web.

2. In a rotary multicolor printing press, base frames, top frames, roll frames and press frames, changeable brackets projecting to the right and left from the press frames, a web supply roll and a web rewind roll carried by the roll frames, two upper series of web guide rollers carried by the top and roll frames and a lower series of web guide rollers carried by the base frames, two adjacent stacks of printing units carried by the press frames, means for leading the web over one of the upper series of guide rollers, through both stacks of the printing units and over the other upper series of guide rollers for non-perfected the web and over the lower series of guide rollers, through both stacks of the printing units and

over said other upper series of guide rollers to the web rewind roll for perfecting the web, and means for reversing the movement of one stack of the printing units when perfecting the web.

3. In a rotary multicolor printing press, web supply and rewind rolls, first and second adjacent stacks of changeable printing units, means for leading the web from the supply roll along one path to and through the first stack and to and through the second stack, for non-perfecting the web, means for changing the web path from the supply roll to and through the first stack and to the second stack for perfecting the web, and change means for driving the printing units of the first stack in one direction when non-perfecting the web and in the opposite direction when perfecting the web.

4. In a rotary multicolor printing press, web supply and rewind rolls, first and second adjacent stacks of changeable printing units, means for leading the web from the supply roll along an upper path to the top printing unit of the first stack, downwardly therethrough and to and through the second stack for non-perfecting the web, means for leading the web from the supply roll along a lower path to the bottom unit of the first stack, upwardly therethrough and to and through the second stack for perfecting the web, and change means for driving the printing unit of the first stack in one direction when non-perfecting the web and in the opposite direction when perfecting the web.

5. In a rotary multicolor printing press, web supply and rewind rolls, first and second adjacent stacks of changeable printing units, two pairs of selectively used feed rolls for the first stack, means for leading the web along one path from the supply roll to and through one pair of feed rolls to and through the first stack and to and through the second stack, for non-perfecting the web, means for leading the web from the supply roll along another path to and through the other pair of feed rolls to and through the first stack and to the second stack for perfecting the web, and change means for driving the printing units of the first stack in one direction when non-perfecting the web and in the opposite direction when perfecting the web.

6. In a rotary multicolor printing press, web supply and rewind rolls, first and second adjacent stacks of changeable printing units, two pairs of selectively used feed rolls for the first stack, means for leading the web along one path from the supply roll to and through one pair of feed rolls, to and through the first stack and to and through the second stack for non-perfecting the web, means for leading the web from the supply roll along another path to and through the other pair of feed rolls to and through the first stack and to the second stack for perfecting the web, and means including change gears for driving the printing units of the first stack in one direction when non-perfecting the web and in the opposite direction when perfecting the web.

7. In a rotary multicolor printing press, web supply and rewind rolls, first and second adjacent stacks of changeable printing units, upper and lower pairs of selectively used feed rolls for the first stack, means for leading the web along an upper path from the supply roll to and through the upper pair of feed rolls to the top unit of

the first stack, downwardly therethrough and to and through the second stack, for non-perfecting the web, means for leading the web from the supply roll to and through the lower pair of feed rolls to the bottom unit of the first stack, upwardly therethrough and to the second stack for perfecting the web, and change means for driving the printing units of the first stack in one direction when non-perfecting the web and in the opposite direction when perfecting the web.

8. In a rotary multicolor printing press, web supply and rewind rolls, first and second adjacent stacks of changeable printing units, upper and lower pairs of selectively used feed rolls for the first stack, means for leading the web along an upper path from the supply roll to and through the upper pair of feed rolls to the top unit of the first stack, downwardly therethrough and to and through the second stack for non-perfecting the web, means for leading the web from the supply roll to and through the lower pair of feed rolls to the bottom unit of the first stack, upwardly therethrough and to the second stack for perfecting the web, and means including change gears for driving the printing units of the first stack in one direction when non-perfecting the web and in the opposite direction when perfecting the web.

9. In a convertible rotary multicolor web printing press, web supply and rewind rolls, first and second adjacent stacks of changeable printing units, feed rolls changeably located in upper and lower positions, means for leading the web from the supply roll to and through the feed rolls when located in their upper position and from thence downwardly through the printing units of the first stack and upwardly through the printing units of the second stack for non-perfecting the web, and means for leading the web from the supply roll to and through the feed rolls when located in their lower position and from thence upwardly through the printing units of the first stack, then downwardly and then upwardly through the printing units of the second stack for perfecting the web without changing the elements of the driving means.

HANS J. LUEHRS.
